UNITED STATES PATENT OFFICE.

WILLIAM W. WILLIAMS, OF CORTLAND, NEW YORK.

SANDPAPER-HOLDER.

No. 840,982.

Specification of Letters Patent.

Patented Jan. 8, 1907.

Application filed January 2, 1906. Serial No. 294,193.

To all whom it may concern:

Be it known that I, WILLIAM W. WILLIAMS, a citizen of the United States, residing at Cortland, in the county of Cortland and 5 State of New York, have invented a new and useful Sandpaper-Holder, of which the following is a specification.

This invention relates to sandpaper-holders of that general class designed for use by carpenters, cabinet-makers, and other persons in smoothing and polishing the surfaces of wood and other material, and has for its object to provide improved means for retaining the sandpaper in position on the holder.

15 A further object of the invention is to provide a holder comprising relatively stationary and movable clamping members, one of which is provided with an operating-handle which forms a pocket or compartment for the 20 reception of a roll of sandpaper.

25 A further object is to form one end of the stationary clamping member with an angular extension and the opposite end thereof with a curved or rounded portion, so that the device may be used for smoothing the walls 30 of concavities and angular depressions or projections.

35 A still further object is to form the clamping members with interengaging parts, whereby said members are effectually locked 40 against accidental lateral displacement.

With these and other objects in view the invention consists in the construction and novel combination and arrangement of parts hereinafter fully described, illustrated in the accompanying drawings, and pointed out in the claims hereto appended, it being understood that various changes in form, proportions, and minor details of construction may 45 be resorted to without departing from the principle or sacrificing any of the advantages of this invention.

50 In the accompanying drawings, forming a part of this specification, Figure 1 is a perspective view of a sandpaper-holder constructed in accordance with my invention. Fig. 2 is a longitudinal sectional view. Fig. 3 is a perspective view of the movable clamping member detached, and Fig. 4 is a similar view of the stationary clamping member or base of the holder detached.

55 Similar numerals of reference indicate corresponding parts in all the figures of the drawings.

The improved device consists of a substantially rectangular body portion or sta-

tionary clamping member 5 and a movable spring clamping member 6, the latter having its central portion curved or bowed upwardly to form a transversely-disposed operating-handle 7. The stationary member 5 is provided with a flat base 8, which forms a bearing-surface for a strip of sandpaper or other abrading material 9, one end of which is coiled into a roll 10 and seated in the pocket 65 or magazine 11, formed by the handle 7.

One end of the stationary member 5 is bent upwardly to produce an angular extension or lip 12, while the opposite end thereof is curved upwardly at 13 and thence downwardly to form a depending lip 14, the strip of sandpaper being clamped between the lips 12 and 14 and corresponding lips 15 and 16, formed on the opposite ends of the movable clamping member 6.

As a means for preventing accidental lateral displacement of the members 5 and 6, the lower or stationary member 5 is formed with an upturned lug 17, adapted to engage a corresponding depression 18 in the adjacent face of the movable member 6.

In operation the roll of sandpaper is inserted in the pocket 11 and one end thereof passed between the lips 15 and 16 and thence beneath the bearing-surface 8 and over the lip or extension 12, being clamped in engagement with said lip by the lip 16 on the movable clamping member 6. When the exposed surface of the sandpaper has become worn, the latter may be severed and a fresh surface presented to the wood by releasing the clamping member 6 and drawing a fresh strip from the roll across the bearing-surface and clamping the same in engagement with the lips 12 and 16, as shown.

Attention is called to the fact that the spring clamping action of the sides of the handle serves to retain the roll of sandpaper within the pocket and also causes the terminal lips of the movable member to yieldably engage the sand-paper and clamp the latter in engagement with the lips on the stationary member. It will also be observed that by having one end of the stationary clamping member disposed at an angle and the opposite end thereof curved the holder may be conveniently used for smoothing and polishing the walls of curved and angular depressions or projections.

To release the movable clamping member, it is merely necessary to grasp the stationary member and exert an inward pressure on the

side walls of the handle, when the two members may be readily detached.

I claim—

1. A device of the class described, comprising relatively stationary and movable clamping members, one of which is provided with means for holding a roll of abrading material adapted to cover the exposed surface of the opposite member, and a lug formed on one member and engaging a depression in the adjacent member for preventing lateral displacement of said members.
2. A device of the class described comprising relatively stationary and movable clamping members, one of which is provided with means for holding a roll of abrading material adapted to cover the exposed surface of the opposite member; said members being provided with interlocking parts.
3. A device of the class described comprising a stationary clamping member, and a movable spring clamping member provided with a handle defining a pocket adapted to receive a roll of abrading material, one end of which is clamped between said members and covers the exposed face of the stationary member.
4. A device of the class described comprising relatively stationary and movable clamping members provided with terminal upwardly-extending lips, one of said members

being provided with means for holding a roll of abrading material, the end of which covers the exposed surface of the opposite member and is clamped in position by engagement 35 with said lips.

5. A device of the class described, comprising relatively stationary and movable clamping members provided with interlocking parts, and formed with terminal upwardly-extending lips, and a strip of abrading material covering the exposed face of one of the members and clamped in position between said lips.

6. A device of the class described comprising a stationary clamping member, one end of which is provided with an angular extension forming an upwardly-extending lip and the opposite end thereof provided with a curved portion terminating in a depending 45 lip, a movable clamping member provided with corresponding lips, and a strip of abrading material covering the exposed surface of the stationary clamping member and interposed between said lips.

In testimony that I claim the foregoing as my own I have hereto affixed my signature in the presence of two witnesses.

WILLIAM W. WILLIAMS.
